UNITED STATES PATENT OFFICE.

MILLARD E. STOCKWELL, OF MONROVIA, CALIFORNIA.

INTERNAL-COMBUSTION ENGINE.

1,342,723.

Specification of Letters Patent.

Patented June 8, 1920.

Application filed March 12, 1919. Serial No. 283,279.

To all whom it may concern:

Be it known that I, MILLARD E. STOCKWELL, a citizen of the United States, and a resident of Monrovia, in the county of Los Angeles and State of California, have invented new and useful Improvements in Internal-Combustion Engines, of which the following is a specification.

This invention relates to improvements in engines of the internal combustion type and adapted to employ air, gas, oil, or other fuels, and an object of this invention is to provide an engine capable of operating as a two cycle engine but employing practically the four cycle principle.

It is also an object of this invention to provide an engine in which an augmented impulse is had upon each working stroke of the main piston, secondary or auxiliary impulses being supplied by heating secondary charges of suitable elements, such as air, or other expansive elements during the working stroke.

It is a further object to provide in an internal combustion engine a main, or firing cylinder capable of utilizing gas, or other suitable fuels, for imparting the primary impulse to the main piston therein, and auxiliary cylinders and pistons for compressing other elements such as air and adapted to be delivered at timed intervals to the firing cylinder for imparting additional impulses to the main piston.

It is a further object to provide in an engine of the character referred to a main cylinder and an auxiliary cylinder of greater area than said main cylinder, with suitable connections and having separate pistons operated from a common crank shaft, whereby the main cylinder may be charged with a suitable fuel for imparting an initial impulse to the piston therein and another element, air for instance, may be compressed in the auxiliary cylinder and delivered to said main cylinder for imparting additional impulse to the main piston.

Another object is to provide a two cycle compound internal combustion engine adapted to use any kind of suitable fuel or elements and adapted to be cooled by air or water, provided with a substantially long stroke and utilizing the well known principle of the steam engine in which the piston is followed with an expansive element after the initial movement. It will be understood that in any internal combustion engine, the

force exerted on the pistons constantly decreases as the piston nears the end of its travel, for the reason that the expansion of the gas attains a maximum pressure immediately after the explosion and as the piston moves thereafter the force is decreased as the gas assumes its normal state. It is an object, therefore, in this invention, to provide means for supplying a substantially constant force for application to the piston in the main cylinder subsequent to the explosion in order that a greater efficiency may be had in the operation. Other objects may appear as the description progresses.

My invention comprises certain novel features, details and arrangements of parts as will be hereinafter more fully described and claimed.

In the accompanying drawings forming a part of this application:

Figure 1 is a sectional elevation of my improved engine, with the pistons shown at the first quarter of a stroke;

Fig. 2 is a diagram of the same with the pistons shown at the second quarter of a stroke;

Fig. 3 is a like diagram with the pistons shown at the third quarter of a stroke;

Fig. 4 is a plan of my engine;

Fig. 5 is a transverse sectional elevation of the same;

Fig. 6 is a fragmentary side view of the auxiliary cylinder head;

Fig. 7 is a plan of the main cylinder head;

Fig. 8 is a transverse sectional plan of the main cylinder.

The engine forming the subject matter of the present invention is designed to afford a structure in which the heat developed by the compressed charges of fuel in the main cylinder, after imparting a primary impulse to the primary piston may be caused to do further work by heating and expanding auxiliary charges of compressed elements so as to actuate the auxiliary pistons. The engine is also designed to impart a primary impulse and then a secondary impulse which is effective in turning the crank shaft at the time when the crank or cranks are traveling through their arc of greatest leverage.

In every instance the auxiliary charges of compressed elements are expanded by the heated products from the main cylinder, regardless of whether the said heated products are heated by explosions or by com-

pression. The primary piston of my engine is so designed that in operation a portion thereof is adapted to compress charges of suitable elements for the main cylinder when 5 moving in one direction and to compress charges of another element when moving in an opposite direction.

In the drawings, which I will now describe in detail, 1 is a suitable crank case 10 which forms a base upon which the several parts of my engine are mounted, and 2, 2 are removable ends therefor which are held by means of bolts 3, 3, etc., in alined positions on the opposite ends of the crank case 15 1 and have bearings 4, 4 therein for rotatably supporting a crank 5.

In the form of engine shown, known as the V type motor, a duplex primary cylinder C is mounted at an angle of about 45 20 degrees on one side of the crank case, and is composed of two separate portions 8 and 9, the lower end of part 8 being attached by bolts 6, 6, etc., to the crank case 1, and the upper part 9 being attached to the part 25 8 by means of bolts 10, 10, etc., through flanges 11 and 12, on the parts 8 and 9, respectively. Upper part 9 has a head 13 attached thereto by means of bolts 14, 14, etc., and a plurality of annular ribs 15, 15, 30 etc., are provided on part 9 for cooling the cylinder during the operation of the engine.

A primary piston P is provided in primary cylinder C and has an enlarged lower 35 portion 16 which operates in the enlarged lower part 8 of said cylinder and a reduced portion, or head, 17 which operates in the reduced part 9 of said cylinder, both upper and lower portions being provided with 40 suitable rings 18 and 18', respectively, as shown.

Piston P is connected with the central offset portion 19 of the crank 5 by means of a suitable connecting rod 20 and a fuel 45 pipe 21 is connected with the upper end of cylinder part 8 and is adapted to lead to a carbureter or generating valve, not shown, by means of which a suitable fuel may be supplied primarily to part 8 of the cylinder.

50 The head 13 of the cylinder C has a fuel inlet chamber 22 formed integral therewith and above the top thereof, which is connected by means of a pipe 23 with the cylinder part 8, a check valve 24 being interposed in said pipe for preventing a return or back pressure forcing the elements transported through said pipe to the point of origination. A valve 25 is positioned in the head 13 at the bottom of inlet chamber 55 22 and is adapted to be held normally closed by means of a spring 26 which is carried on the stem 27 thereof, said stem being slidably held in a boss 28 formed on the head 13. One or more spark plugs 29 may be 60 threaded into the head 13 and extended into 65

the combustion chamber of cylinder part 9, as shown, or an electric burner may be employed with certain classes of fuel, such as oil, or when air is to be heated for operating the primary piston P.

70 On the opposite side of crank case 1, from cylinder C and disposed at about the same angle, I provide an auxiliary cylinder A, attached at the bottom by means of bolts 30 to the crank case 1. This auxiliary cylinder is of substantially greater diameter and area than cylinder C, and has a removable head 31 attached thereto by means of bolts 32. An inlet chamber 33 is formed on the top of head 31 and is provided with a valve 34, which is held normally closed by means of a spring 35 carried on its stem 36, said stem being slidably held in a boss 37 formed on the head 31. Chamber 33 is connected by means of a pipe 38, with the interior of the crank case 1 and by means of a pipe 39, a port 40 in cylinder A is connected with a port 41 in cylinder C. An auxiliary piston 42 having rings 43 is slidably held in cylinder A and is operably connected by means of a connecting rod 44 with the portion 19 of the crank shaft 5, the crank end of said connecting rod being bifurcated for receiving the crank end of connecting rod 20 between the bifurcations 95 thereof, as shown.

An air inlet pipe 45 is connected with one end of the crank case 1, and a check valve 46 of suitable design is provided thereon, so that during the operation of the pistons 100 air may be drawn into the crank case 1 through said valve, while on reverse strokes of the pistons said valve will prevent the emission of the air therefrom, for purposes to be hereinafter described.

105 In operation, the primary piston P on its initial down stroke will induce a flow of gas, or other fuel into the cylinder part 8 through pipe 21 and at the same time piston 42 will induce a flow of air from the 110 crank case 1 through pipe 38 into the upper end of cylinder A. On the up-stroke of piston P, the charge of gas or fuel in part 8 of cylinder C will be forced through pipe 23 and inlet chamber 22 into the upper end 115 of cylinder part 9, check valve 24 serving for the purpose of retaining the charge and valve 25 in head 13 being open for admitting the gas to cylinder C. The gas is then compressed further in portion 9 of cylinder C and fired by means of the spark plugs 29, whereupon piston P is again moved downward on a power stroke, while piston 42 in cylinder A is continued in its upward movement and compresses a volume of air 120 from the crank case 1, which has been drawn thereinto on the down stroke.

125 When the crank and pistons are set at the first quarter of a stroke, as shown in Fig. 1, piston P will have had an initial movement 130

caused by the expansion of the heated gas in cylinder C for one half of a complete stroke and piston 42 will have attained the end of its compression stroke as shown. At 5 this time and when said pistons are in the position's stated, the compressed air from cylinder A will begin exhaust through port 40 and pipe 39 into cylinder C, and as pistons P and 42 move downward from said 10 positions, the charge of compressed element admitted to cylinder portion 9 will provide an additional impulse for piston P and serve to complete the power stroke of said piston. Port 41 of portion 9 will remain open until 15 piston P attains the third quarter of its stroke, then it will be again closed, and at this instant, piston 42 will exhaust the elements in cylinder A through an exhaust pipe 47, which is attached to said cylinder at a 20 point midway of its ends.

Thus it will be seen that after an initial downward movement of the pistons, a charge of fuel will be compressed in pipe 23 and inlet chamber 22 by each upward movement of piston P and each downward stroke of said piston will draw the charge into cylinder C in readiness for further compression by the up stroke of the piston. Likewise each down stroke of piston 42 will force 25 a charge of air from the crank case into the inlet chamber of cylinder A and each up stroke of said piston will compress said charge and force the same at a predetermined time into cylinder C. The exhaust 30 from cylinder C is through pipe 39 and cylinder A, and exhaust pipe 47, and it will be seen that both the primary and auxiliary cylinders and the crank case will be thoroughly scavenged of consumed gases at each 35 operation of the pistons.

While reference has been made in the foregoing description to the employment of explosive elements, it will be apparent that by proportioning the parts of the primary cylinder and piston so as to secure a very high degree of compression, that other fuels such as crude oil, may be employed instead of gasoline or elements which readily mix with air for forming highly explosive mixtures.

50 It will be understood that the specific form and arrangement of parts, except as may have been particularly stated, or the formation thereof, may be altered or modified to suit conditions in different forms and 55 sizes of engines and according to the kind of fuel used for operating the same, and I do not limit myself to any particular forms, except as I may be limited by the appended claims.

60 What I claim is:

1. An air and gas engine having tandem cylinders, a double piston operating therein, an auxiliary cylinder adapted to be heated by the exhaust from the principal cylinder, 65 the double piston being capable of compress-

ing charges in the principal cylinder and exhausting into said auxiliary cylinder, the expansion of said charges operating to impart a plurality of impulses to the said piston upon each working stroke. 70

2. An engine of the character described, comprising a primary cylinder having firing and compression portions of different diameters, a double piston operating therein, an auxiliary cylinder having a piston therein, means for imparting an initial impulse to said primary piston in said firing cylinder, a pipe connecting said auxiliary cylinder with the firing portion of said primary cylinder and arranged so that an element 75 compressed in said auxiliary cylinder may be exhausted into said firing cylinder for imparting a secondary impulse to the primary piston. 80

3. An engine having a primary tandem cylinder provided with firing and compression chambers, said firing chamber being arranged to receive charges from the compression chamber and adapted to be heated by the expanding charges in the firing chamber, a duplex piston operating in said firing and compression chambers, an auxiliary cylinder communicating with said firing chamber and means in said cylinder for imparting primary and secondary impulses to 90 the engine. 95

4. An engine of the character described having a principal cylinder with firing and compression chambers therein, an auxiliary cylinder connected with said firing chamber 100 and adapted to receive the heated exhaust therefrom, a double piston operating in said principal cylinder and adapted to compress charges of fuel in said firing chamber, a piston in said auxiliary cylinder, explosives 105 in said firing cylinder serving to impart a primary impulse and a compression of an element in said auxiliary cylinder serving to impart a secondary impulse to said primary piston. 110

5. An internal combustion engine having a primary cylinder provided with tandem firing and compression chambers, a duplex piston operating in said firing and compression chambers, an auxiliary cylinder, a piston therein, and means connecting said auxiliary cylinder with the firing chamber of said principal cylinder for affording communication therebetween, said primary piston receiving a charge of fuel in said compression chamber and discharging the same 115 into said firing cylinder, as set forth. 120

6. An engine of the type described having principal and auxiliary cylinders, means for charging the principal cylinder with explosive materials, means for compressing air in the auxiliary cylinder, means for leading the air from the auxiliary cylinder into the principal cylinder before the piston in said principal cylinder has completed its 125 130

- 4
- stroke, whereby secondary impulses are had in driving the engine during each stroke of the piston, and a piston moving in the said principal cylinder and controlling the escape 5 of the exhaust into said auxiliary cylinder.
7. An engine of the character described having a plurality of cylinders arranged for communication at suitable intervals and including a principal cylinder having adjacent 10 cent firing and compression chambers, a primary piston operating in said chambers, a piston for said other cylinder operated by said crank shaft, and connections between said cylinders and controlled by the operation 15 of said pistons, whereby said crank shaft will receive a plurality of impulses from an initial charge on every revolution, one of said cylinders being adapted to receive the exhaust from the engine, and means 20 operable by the force of the exhaust whereby additional work may be accomplished.
8. An internal combustion engine comprising a primary and an auxiliary cylinder, a duplex piston operating in said primary cylinder, 25 said primary cylinder having tandem chambers, means for affording communication between said chambers, means for affording communication between said primary and auxiliary cylinders, a piston in 30 said auxiliary cylinder for compressing an element therein, said duplex piston serving to compress a charge of explosive fuel for delivery to said primary cylinder and also serving to control the connections between 35 said primary and auxiliary cylinders for the purpose described.
9. An internal combustion engine having primary and auxiliary cylinders, a pipe for affording communication therebetween, a 40 crank case, a pipe connecting said auxiliary cylinder with said crank case, a piston in said primary cylinder controlling the connection between said cylinders, and a piston in said auxiliary cylinder for compressing an element for delivery to said primary cylinder.
10. An internal combustion engine having a tandem cylinder comprising separable sections of different diameter and area, fuel 45 supply means connected with the major section thereof, an inlet chamber connected with the minor section thereof and provided with a valve for controlling the admission of an element thereto, a duct connecting said major section with said inlet chamber, and a piston having major and minor portions operating in said major and minor sections, respectively, the major section of said piston receiving a charge of an element and supplying the same to said minor section, means 55 for heating the element for operating said piston, an auxiliary cylinder and a duct leading to the minor of said tandem cylinder, for the purpose set forth.
11. An internal combustion engine comprising a tandem primary cylinder having a common piston therein, an auxiliary cylinder connected with said tandem cylinder, a piston in said auxiliary cylinder, a crank shaft common to said pistons, and connections between and with said cylinders whereby an explosive element may be supplied to 60 said tandem cylinder for imparting an initial impulse to the piston therein and for compressing a charge of a secondary element for delivery to said tandem cylinder for imparting secondary impulses to said piston.
12. An internal combustion engine comprising a crank case, a crank shaft mounted therein, a duplex primary cylinder attached to said crank case, an auxiliary cylinder also attached thereto, a primary duplex piston in said primary cylinder and connected with said crank shaft, a piston in 65 said auxiliary cylinder and also connected with said crank shaft, a pipe connecting said crank case with said auxiliary cylinder, a pipe connecting said primary and auxiliary cylinders, fuel supply means for said primary cylinder, and valve means for controlling the supply and exhaust of elements of different character to said primary and auxiliary cylinders, as set forth.
